UNITED STATES PATENT OFFICE

CLARENCE D. BARR, OF BIRMINGHAM, ALABAMA, ASSIGNOR TO AMERICAN CAST IRON PIPE CO., OF BIRMINGHAM, ALABAMA, A CORPORATION OF GEORGIA

PIPE-HEATING APPARATUS

Application filed September 6, 1929. Serial No. 390,716.

This invention is an improvement in pipe heating apparatus, and more particularly in an oven for heating cast iron pipe preparatory to coating the same with asphalt, tar, or the like.

Cast pipes are usually coated by dipping them in a substance, such as asphalt, tar, or the like, the substance being brought into and retained at the proper consistency by means 10 of heat.

The depth or thickness of the coating depends, among other factors, upon the temperature of the coating material, and to attain a selected thickness over a series of successive 15 operations, it is apparent that the temperature of the composition must be maintained constant.

Not only must the heat applied to the composition be constant, but the temperature of 20 the pipes to be coated must be taken into consideration. If the pipes are colder than the composition, the coating will be thicker, while if the pipes are hotter than the composition, the coating will be thinner.

25 This is due to the abstraction of heat from that portion of the composition in contact with the pipes, or to the addition of heat to such portion from the pipe, so that unless there is correspondence between the temperatures of pipe and composition, the coating 30 will not be uniform.

One of the primary objects of the present invention is the provision of an apparatus 35 enabling castings, such as pipes, to be heated to a selected temperature, with the distribution of heat uniform throughout the length and the circumference of the pipe.

Another object is the provision of apparatus, enabling rapid and uniform heating of 40 the pipes, by direct impingement of a flame, thus to lessen the time required for uniform heating, to obtain economy in fuel and operation.

45 With these and other objects in view the invention consists in the construction and novel combination of parts fully described hereinafter, illustrated in the accompanying drawings, and pointed out in the claims appended hereto, it being understood that various changes in the form, proportion, size

and minor details of construction within the scope of the claims, may be resorted to without departing from the spirit of the invention.

In the drawings forming a part hereof:—

Fig. 1 is a plan view of the improved apparatus.

Fig. 2 is an end view with parts in section.

Fig. 3 is a side view.

In the present embodiment of the invention, a suitable frame is provided, consisting of columns 1 mounted on a base 2, and supporting girders 3 at their tops. A skeleton structure 4 is carried by the girders between the columns, as shown in Fig. 3, the said structure tapering toward its lower end, as shown, and carrying cross plates 5 near the said lower end. The heating apparatus is arranged below the structure 4, between the columns, and a hood is provided for covering the pipes in the oven during the heating.

The hood is composed of similar sections 6, each of which is flanged downwardly as shown, at its outer side and ends, and the sections are hinged to a common connection 7, at the bottom of the structure 4, so that the sections may swing upwardly and downwardly as indicated in full and dotted lines in Fig. 3. A flexible member 8 is connected to the outer side of each section, and these flexible members extend inwardly and upwardly to a connection with another member 9. Referring to Fig. 1, it will be seen that the connections between the flexible members 8 and the hood sections are by means of stirrups 10, the stirrup arms being pivoted to the hood section, while the flexible member is connected to the body of the stirrup.

The flexible member 9, passes over a pulley 11 journaled on the structure 4, over a second pulley 12, journaled on a superstructure 13, on the girders 3, to operating mechanism for the hood. This mechanism includes a cylinder 14, in which is arranged a piston 15. The flexible member from the pulley 12 passes beneath the pulley 16 at the bottom of the cylinder, and upwardly over a pulley 17 journaled at the top of the piston. From the pulley 17, the flexible member passes to a suitable fixed connection, and it will be ap-

parent that when the piston moves upward, the connections 8 are moved upward, and the hood sections are lifted, as indicated in dotted lines in Fig. 3.

Mechanism is provided for automatically engaging the hood sections when elevated, and for holding them in such position. This mechanism comprises angle latches 18, pivoted at 19 to the cross plates 5 before mentioned. Each of the angle latches normally occupies the position shown in Fig. 3, on the angle plates. Each hood section has pins 21 for engaging notches in the lower ends of the angle latches, and the latches are so positioned that when the hood sections are lifted into the dotted line position of Fig. 3, the pins will engage and slightly move the latches to enable them to move into the notches 22 of the latches.

The structure 4 depends at each end of the frame, leaving the space between the two depending ends clear, so that no impediment is offered to the upward swinging of the hood sections. Referring to Fig. 3, it will be noticed that the inner lower corners of the end flanges of the hood sections are cut away, as shown at 23. The oven with which the hood cooperates is arranged directly below the hood, so that when the hood sections are in the position of Fig. 3, they will rest upon the defining wall of the oven.

The oven, which is composed of concrete or the like, is an open box, composed of a bottom 24, and side and end walls 25 and 26, and the upper edges of the side and end walls serve as a seat for the flanged edges of the hood sections when they are in lowered position. A number of pairs of rollers 27 is supported in the oven. These rollers are mounted on stub shafts 28, which are journaled in cross bearing plates 29 supported by the oven body.

The members of each pair are in register, and spaced apart longitudinally of the oven body, and the members of each pair lap the members of the succeeding pair, as shown in Figs. 1 and 2. Each pipe 30 is supported by four rollers, that is, by two pairs, as clearly shown in Fig. 2, and the pipes are rotated during the heating, so that every part thereof is subjected to the action of impinging flame to uniformly heat the same, by means of the rollers 27. Each stub shaft 28 has a pinion 31, which meshes with another pinion 32 journaled below the pinion 31, and between the pinion and the similar pinion on the adjacent stub shaft 28. That is, each pinion 32 meshes with two pinions 31. The pinions 31 and 32 are of the same size, and the stub shaft 28a of the central pinion 31 is extended through the adjacent end wall of the oven body, and is connected to a suitable motor 34, an electrical motor in the present instance, by means of a chain and sprockets 35, the chain connecting sprockets on the stub

shaft and on the motor shaft. A speed reducer 36 is arranged between the motor and the sprocket wheel driven thereby.

When pipes are mounted on the rollers 27, all of said rollers are driven at the same speed, and relatively slowly, thereby to rotate the pipes continuously while they are in the oven. The pipes are heated by means of gas, a series of cross pipes 37 being arranged beneath the pipes when they are on the rollers 27. The pipes 37 are connected with a common header 38, and each of the pipes is perforated on its upper side, as at 37a, throughout that portion of the pipe which is within the oven to enable the escape of gas.

The pipes are arranged substantially the full length of the oven body, so that the entire length of the pipe mounted on the rollers is subjected to the action of the flaming gas issuing from the perforations of the pipes 37.

The pipes to be heated are conducted to the oven on rails 39 supported by pedestals 40. Rails 41 are arranged transversely of the oven body between the sets of rollers 27, and each rail 41 is pivoted at the opposite side of the oven from the rails 39 to a support 43. The opposite ends of the rails are connected by a cross bar, and the cross bar at its center rests in a stirrup 44 at the upper end of a piston 45 arranged in a cylinder 46.

Normally the rails 41 occupy the position shown in full lines in Fig. 2, and in such position the upper edges of the rails are below the bottoms of the pipes on the rollers 27. When it is desired to insert pipes in the oven, fluid under pressure is admitted to the cylinders 14 and 46. The piston 15 lifts the hood sections into the dotted line position of Fig. 3, thus leaving the interior of the oven accessible. At the same time the rails 41 are lifted into the dotted line position of Fig. 2, and the pipes to be heated, resting on the rails 39, are rolled upon the rails 41, and positioned with respect to the rollers 27. The cylinders 14 and 46 are now permitted to exhaust, the rails 41 move downward, and the pipes 30 come to rest upon the rollers 37. At the same time or soon thereafter, the hood sections move down into the full line position of Figs. 2 and 3.

The hood sections may be operated independently of the rails, or in sequence therewith. When the hood sections are lifted to the proper position, they are so held by the latches 18. When the pipes are on the rollers 27, they are rotated at a relatively slow speed, so that every part of each pipe throughout its length and circumference is subjected to the action of the flaming gas issuing from the perforations of the pipes 37.

When the pipes have been heated to the proper temperature, fluid under pressure is again admitted to the cylinders 14 and 46, the hood sections are lifted, as are also the pipes, and they are rolled out upon the rails

39, which conduct them to the coating mechanism. The pipes reach the fluid coating composition at exactly the temperature desired, so that the depth of the coating may be nicely gauged. When pipes are too hot, the coating composition is heated by contact therewith, and the coating is thinner than is perhaps desired. If the pipes are cooler than the composition, the coating is perhaps too thick, the composition being cooled by contact with the pipes. By heating the pipes to a selected temperature, with a selected temperature of the coating composition, the depth of coating may be nicely calculated.

15 It will be noticed referring to Fig. 2, that the rails 41 extend through and beyond the side walls of the oven body, which are suitably notched to enable the passage of the rails. One side wall is also notched or provided with openings for the passage of the pipes 37, and the motor and the cylinder 46 are arranged within a pit 47.

What is claimed as new is:—

20 25 30 35 40 45 50 55 60 65 70 75 80 85 90 95 100 105 110 115 120 125 130

25 1. In apparatus of the class described, means to support and rotate pipes to be heated, including sets of rollers, the rollers of each set registering with the corresponding rollers of the other set, and adjacent rollers lapping, means to rotate the rollers, and heating pipes extending transversely of the axes of the rollers.

30 35 40 45 50 55 60 65 70 75 80 85 90 95 100 105 110 115 120 125 130

30 2. In apparatus of the class described, means to support and rotate pipes to be heated, including sets of rollers, the rollers of each set registering with the corresponding rollers of the other set, and adjacent rollers lapping, means to rotate the rollers, heating pipes extending transversely of the axes of the rollers, an open top oven in which the rollers and pipes are mounted, and a movable hood for closing the top of the oven and enclosing the pipes to be heated.

35 40 45 50 55 60 65 70 75 80 85 90 95 100 105 110 115 120 125 130

35 3. In apparatus of the class described, means to support and rotate pipes to be heated, including sets of rollers, the rollers of each set registering with the corresponding rollers of the other set, and adjacent rollers lapping, means to rotate the rollers, heating pipes extending transversely of the axes of the rollers, an open top oven in which the rollers and pipes are mounted, a movable hood for closing the top of the oven and enclosing the pipes to be heated, said hood composed of similar sections hinged on a line transverse to the center of the oven, and means to raise and lower the outer sides of the sections.

40 45 50 55 60 65 70 75 80 85 90 95 100 105 110 115 120 125 130

40 4. In apparatus of the class described, means to support and rotate pipes to be heated, including sets of rollers, the rollers of each set registering with the corresponding rollers of the other set, and adjacent rollers lapping, means to rotate the rollers, heating pipes extending transversely of the axes of the rollers, an open top oven in which the roll-

ers and pipes are mounted, a movable hood for closing the top of the oven and enclosing the pipes to be heated, said hood composed of similar sections hinged on a line transverse to the center of the oven, means to raise and lower the outer sides of the sections, and latches operated by the upward movement of the sections beyond a selected point to lock them in lifted position.

5. In apparatus of the class described, an oven having an open top, and provided with sets of rollers near the opposite ends thereof, corresponding rollers of the sets being in register, and each roller lapping the adjacent rollers, means for rotating the rollers, and heating pipes arranged transversely of the oven, and the axes of the rollers.

6. In apparatus of the class described, means to support and rotate pipes to be heated, an oven having heating means in which the supporting means is arranged, and a movable top for the oven, said top including a hood composed of similar sections hinged at approximately the center of the oven, and means for raising and lowering the outer free sides of the sections.

7. In apparatus of the class described, means to support and rotate pipes to be heated, an oven having heating means in which the supporting means is arranged, and a movable top for the oven, said top including a hood composed of similar sections hinged at approximately the center of the oven, means for raising and lowering the outer free sides of the sections, and latches for automatically engaging and holding the sections lifted when they pass above a selected point.

8. In apparatus of the class described, an oven having an open top, a sectional hood movable into and out of position above the oven to close and open the top, means within the oven and below the level of the top thereof to support and rotate a plurality of pipes on their longitudinal axes, and means to simultaneously raise and lower the pipes into and out of engagement with the rotating means.

9. In apparatus of the class described, an oven having an open top, a sectional hood movable into and out of position above the oven to close and open the top, means within the oven and below the level of the top thereof to support and rotate a plurality of pipes on their longitudinal axes, and means to simultaneously raise and lower the pipes into and out of engagement with the rotating means, said raising means including rails pivoted at one side of the oven and passing beneath the pipes when supported on the rotating means, and hydraulic mechanism connected with the other end of the rails.

10. In apparatus of the class described, an oven having sets of rollers journaled therein, the rollers of each set being in register with the corresponding rollers of the other set,

and the rollers of each set lapping adjacent rollers, the pairs of lapping rollers of the sets being adapted to support a pipe or the like, and means to rotate the rollers at the same speed, and a plurality of lines of fuel jets arranged beneath the pipes to heat them as they are rotated.

11. In apparatus of the class described, an oven having sets of rollers journaled therein, the rollers of each set being in register with the corresponding rollers of the other set, and the rollers of each set lapping adjacent rollers, the pairs of lapping rollers of the sets being adapted to support a pipe or the like, and means to rotate the rollers at the same speed, a plurality of lines of fuel jets arranged beneath the pipes to heat them as they are rotated, said oven having an open top, and a hood movable into and out of position to close the top.

12. In apparatus of the class described, an oven having sets of rollers journaled therein, the rollers of each set being in register with the corresponding rollers of the other set, and the rollers of each set lapping adjacent rollers, the pairs of lapping rollers of the sets being adapted to support a pipe or the like, and means to rotate the rollers at the same speed, a plurality of lines of fuel jets arranged beneath the pipes to heat them as they are rotated, said oven having an open top, and a hood movable into and out of position to close the top, said hood composed of sections hinged at approximately the center of the oven and adapted to swing at their free edges upwardly and away from the oven.

13. In apparatus of the class described, an oven having sets of rollers journaled therein, the rollers of each set being in register with the corresponding rollers of the other set, and the rollers of each set lapping adjacent rollers, the pairs of lapping rollers of the sets being adapted to support a pipe or the like, and means to rotate the rollers at the same speed, a plurality of lines of fuel jets arranged beneath the pipes to heat them as they are rotated, said oven having an open top, and a hood movable into and out of position to close the top, said hood composed of sections hinged at approximately the center of the oven and adapted to swing at their free edges upwardly and away from the oven, and means for swinging the sections.

14. In apparatus of the class described, an oven having sets of rollers journaled therein, the rollers of each set being in register with the corresponding rollers of the other set, and the rollers of each set lapping adjacent rollers, the pairs of lapping rollers of the sets being adapted to support a pipe or the like, and means to rotate the rollers at the same speed, a plurality of lines of fuel jets arranged beneath the pipes to heat them as they are rotated, said oven having an open top, and a hood movable into and out of po-

sition to close the top, said hood composed of sections hinged at approximately the center of the oven and adapted to swing at their free edges upwardly and away from the oven, means for swinging the sections, and means operated by the movement of the sections to hold them in lifted position.

15. In apparatus of the class described, an open top oven, means below the top of the oven to support and rotate a plurality of pipes, and means to receive pipes at the level of the top of the oven and lower them onto the rollers, and to deliver pipes from the rollers to the top of the oven, said means including rails hinged to one side of the oven, and lifting means connected with the other ends of the rails.

Signed at Birmingham in the county of Jefferson and State of Alabama this 3rd day of September A. D. 1929.
